UNITED STATES PATENT OFFICE.

FREDERIC C. MORTON, OF CAMBRIDGE, MASSACHUSETTS, ASSIGNOR OF ONE-HALF TO
FRED BURTON CARLISLE, OF CRANSTON, RHODE ISLAND, AND ONE-FOURTH TO
THE GOODYEAR TIRE & RUBBER CO., OF AKRON, OHIO, A CORPORATION OF OHIO.

SHAPING DEVICE FOR TIRE-CARCASSES.

1,278,980.

Specification of Letters Patent. Patented Sept. 17, 1918.

Application filed December 31, 1913. Serial No. 809,685.

To all whom it may concern:

Be it known that I, FREDERIC C. MORTON, a citizen of the United States, residing in Cambridge, in the county of Middlesex and State of Massachusetts, have invented an Improvement in Shaping Devices for Tire-Carcasses, of which the following description, in connection with the accompanying drawings, is a specification, like letters on 10 the drawings representing like parts.

The present invention relates to tire building machinery and is embodied in a novel construction and arrangement of the shaping or spinning-in device which is used to 15 smooth the fabric and shape it on the sides of the core after the fabric has been laid on the periphery of said core, these devices being sometimes described as stitching devices.

The purpose of the invention is to hasten 20 and facilitate the spinning-in or stitching process, without, however, making the operation wholly automatic, since better results can usually be obtained by having the actual operation of smoothing down or shaping 25 the fabric under the control of a skilled workman.

In building a tire carcass in connection with the method to which this invention pertains, strips of fabric are drawn lengthwise 30 over the surface of a rotatable core and partly shaped over the outer periphery of said core while the said core is slowly rotated to draw the fabric into place. After the fabric has been carried wholly around 35 the core, with the middle of the fabric fitted to the periphery of said core, the sides of the fabric are pressed into contact with the sides of the core by means of devices which I shall hereinafter term spinners, which may 40 consist of rotating disks, the peripheries of which are held in contact with the fabric on the core, while the disks themselves are moved in the general direction of their own axes toward the axis of rotation of the core.

In the spinning-in operation, the disks are 45 brought into contact with the fabric at opposite sides of the core and are continually pressed against the sides of the fabric, while they are being moved inwardly with relation 50 to the sides of the core so as to follow the contour thereof throughout.

The machine embodying the invention is provided with spinners operating as above

described, the purpose of the invention being to facilitate the movement of the spinners 55 toward and from the axis of the core and also to provide the spinners with an automatic feed throughout the entire movement toward the axis of rotation of the core, at the same time leaving the lateral movement 60 of the spinners wholly under the control of the attendant, the machine being provided with a manually operated device constituting the sole means for pressing the wiper laterally into contact with the fabric. 65

The invention further relates to means whereby the original point of contact between the spinners and the fabric on the core is automatically controlled; and also to means for producing a rapid feed movement 70 of the spinners toward the core, followed by a slower movement after the spinners are in engagement with the core and performing the function required.

I have used the term "spinners" for convenience throughout the specification and claims; and I wish it to be understood that I mean by this term any device which is capable of being used to press the fabric toward and into firm contact with the surface to which it is to conform, and at the same time to have a continuously changing position with relation to the surface of the fabric so that the pressure is distributed over the said surface during the shaping operation. Apart from these general characteristics, the specific form of spinner which is used may be widely modified without departing from this invention. 80 85

Figure 1 is a plan view partly in section, 90 of a portion of a tire building machine embodying the invention; Fig. 2 is a side elevation of the same, partly in section; and Fig. 3 is a sectional detail taken on line x^3 of Fig. 1, on a larger scale. 95

The machine embodying the invention is provided with the core 1, which is rotatably mounted in the usual way and adapted to be driven at a slow speed while the layer of fabric is being laid around the periphery, 100 after which it is adapted to be driven at a relatively high speed while the sides of the fabric are smoothed into contact with the sides of the core, this mode of operation being old in the art. 105

In accordance with the present invention,

the smoothing of the strip of fabric is accomplished by the action of the spinners 2 which consist of disks mounted so as to be free to rotate at the ends of arms 3 pivotally mounted at 4, on a traveling carriage 5 which is adapted to be moved toward and from the periphery of the core in a direction transverse to the axis of rotation thereof.

10 In the construction shown, I utilize fluid pressure to operate the carriage 5; and the said carriage is shown as connected by a link 6 with a lever 7, which has a cross bar 8, pivoted on a portion of the frame of the machine, one end of said cross bar being connected with a piston rod 9 while the other end of said cross bar is connected through a spring 10 with a fixed part of the apparatus. The piston rod 9 is connected with a piston 12 inside of a cylinder 13 which has a duct 14 leading into it above the piston 12. The said duct is supplied with fluid pressure, compressed air being preferably used, and is controlled by means of a three way cock 15 which is adapted to admit the pressure when in the position shown, or to allow the pressure to escape through an exhaust passage 16, when given a quarter turn.

30 The piston is single acting, that is, movable in one direction only in response to the pressure, the opposite end of the cylinder being provided with a vent passage 17. When the three way cock is turned to admit pressure to the cylinder 13 the piston 12 is forced downward; and through the action of the lever 7 moves the carriage 5 forward so as to bring the wipers 2 into proximity to the core 1.

40 For the purpose of controlling the movement so that the wipers will move rapidly until they come nearly into contact with the fabric, and afterward move slowly during the wiping-in operation, the piston 12 is connected with a dash-pot piston 18, which is shown as directly connected with the piston rod 9 and located in alignment with the cylinder 13. The dash-pot piston 18 travels in a cylinder 19 which is partially filled 50 with some slow flowing liquid, such as glycerin or oil, and the inner wall of the cylinder 19 is provided with a pocket 20 of sufficient capacity to allow the liquid to be freely displaced by the piston 18 during part of the movement thereof, said pocket being so located that the first part of the movement is comparatively free, although sufficiently checked to prevent shocks when the full pressure is turned on. This part 60 of the movement is, therefore, comparatively rapid and the parts are so designed that at the end of this rapid movement the wipers will be almost in contact with the fabric on the core.

65 At the end of this part of the movement,

the dash-pot piston 18 will pass beyond the lower end of the pocket 20 so that the oil in the cylinder 19 can no longer pass through the said pocket. In order, however, that the piston 18 may continue its travel, the dash-pot is provided with a comparatively small by-pass 21 of sufficient capacity to admit of the piston movement, although the resistance is greatly increased. This by-pass 21 is shown as provided with 75 an adjustable valve 22, so that the speed of the carriage during this part of the operation can be regulated. The forward movement of the carriage 5 is limited by means of an adjustable stop 23 which comes in contact with a bumper 24. After the operation has been finished, the carriage is restored to its original position by turning the three way cock 15 to allow the pressure to exhaust from the cylinder 13 so that the 85 action of the spring 10 is unimpeded. Furthermore, the piston 18 is provided with a number of vent orifices 25 controlled by a check valve 26 which allows the piston to travel freely through the liquid in the 90 cylinder.

In order that the spinners 2 may always meet the core in the same position relative thereto, the said spinners are held in the position shown in Fig. 1 during the preliminary feed movement, by means of adjustable stops 27 at opposite sides of the support 28 on which the wiper carriage travels, the said stops engaging the ends of the pivoted levers 3 which are held in 100 engagement with the stops through the agency of a manually operated device, herein shown as a rotatable rod 29 having oppositely inclined screw threads engaging with internally threaded nuts 30 swiveled on the levers 3, the said rod being provided with a hand wheel 31, which is connected with the rod by a yielding connecting device such as a spring 32.

In the construction shown the hand wheel 110 31 has a free bearing on the rotatable rod 29, motion being transmitted from the hand wheel to the rod through the spiral spring 32, one end of which is connected to the hand wheel and the other end to the rod. 115 The rod is provided at the middle with a disk 33 which projects into a notch 34 formed in a block 35 mounted on the carriage, the notch being somewhat wider than the disk thus affording an opportunity for 120 a certain play in the operation of the levers and wipers so that these parts can adjust themselves to irregularities in the surface of the fabric during the spinning-in operation.

125 At the end of the spinning-in operation when the parts are to be restored to the starting position, the hand wheel is released and the spinners are then automatically spread apart through the action 130

of the spring 36 so that in the return movement of the carriage the spinners clear the sides of the core.

The operation of the machine may be briefly described as follows:

After the strip of fabric has been laid on the core, the attendant holds the hand wheel and exerts pressure thereon tending to turn the said wheel. He then opens the pressure cock, upon which the carriage moves forward rapidly until the spinners are nearly in contact with the fabric on the core, the said spinners during the first part of the movement being positively held in a certain pre-determined position with relation to the core by the adjustable stops 27. As the carriage continues its forward movement the spinner levers are released by the stops and the spinners come into contact with the fabric through the pressure exerted on the hand wheel; and this initial position of contact with relation to the core is the same at every operation. As the spinners travel along the surface of the core they are necessarily spread apart, to admit of which movements the attendant allows the hand wheel to move backward, the pressure which he exerts in resistance to this movement being dependent upon his judgment. The play which is provided for by the disk 33 allows the spinners to adjust themselves to slight irregularities in the surface of the fabric while the spring 32 relieves the attendant of the vibration.

After the spinners have passed the widest part of the core, the pressure upon the fabric is maintained by turning the hand wheel and the carriage is finally stopped at the end of its movement by the bumper 24. This finishes the operation. The handle is then released, allowing the spinners to spread apart; and the carriage is restored by the action of the spring 10 after manipulating the three way cock which controls the pressure.

What I claim is:

1. In a tire-building machine, the combination with a rotatable core adapted to receive a strip of fabric; of a spinner; means including a pressure-fluid operated device for automatically moving said spinner toward the axis of rotation of the core and also for constantly maintaining it in yielding engagement with the core; and a manually operated device associated with the spinner and constituting independent means for pressing it into contact with the fabric on the core.

2. In a tire building machine, the combination with a core adapted to receive a strip of fabric; of a spinner; means for automatically moving said spinner toward the axis of the core; means for exerting pressure on said spinner tending to move it toward the side of the core; and means for preventing the effectual operation of said pressure until

the spinner is nearly in contact with the fabric on the core.

3. The combination with a shaping core; of a spinner; means for automatically moving said spinner toward the axis of the core; a manually operated device adapted to move said spinner toward the side of the core; and stops adapted to prevent the effectual operation of said device during the first part of the spinner movement.

4. The combination with a shaping core; of a spinner; means for automatically moving said spinner toward the axis of the core; a manually operated device adapted to move said spinner toward the side of the core; stops adapted to prevent the effectual operation of said device during the first part of the spinner movement; and means for adjusting said stops.

5. The combination with a shaping core; of a spinner mounted on a pivotally supported lever movable toward the axis of the core; means for rocking said lever on its pivot to move the spinner toward the side of the core; and a stop to prevent the rocking movement of the lever throughout a portion of its movement toward the axis of the core.

6. The combination with a shaping core; of a spinner; a carriage for said spinner; means for moving said carriage toward the axis of said core; and means for controlling said movement whereby that part of the movement which brings the spinner nearly to the core is more rapid than the subsequent movement.

7. The combination with a shaping core; of a spinner; a carriage for said spinner; means for moving said carriage toward the axis of said core; means for controlling said movement whereby that part of the movement which brings the spinner nearly to the core is more rapid than the subsequent movement; and means for restoring the carriage to its original position after the operation has been finished.

8. The combination with a rotatable shaping core; of a traveling carriage adapted to move toward and from the axis of said core; spinners secured to the ends of levers pivotally connected with said carriage; a spring connecting the said levers and tending to separate the spinners; a manually operated screw-threaded rod cooperating with the levers to draw the spinners toward each other; and stops limiting the movement of said screw-threaded rod during a portion only of the movement of the carriage.

9. In a tire building machine, the combination with a spinner carriage; of an actuating device for said carriage adapted to be operated by a constant pressure; and means for controlling the rate of movement of said carriage which consists of a dash pot having a cylinder and piston, and means for permitting a relatively free movement of

said piston during a portion of its movement in the dash pot; and for restricting said movement during another part thereof.

10. In a tire building machine, the combination with a spinner carriage; of a cylinder adapted to receive fluid pressure; a piston in said cylinder and connected with said carriage to produce the movement thereof; a dash pot cylinder; a piston in the said dash pot cylinder connected with the main piston; a pocket in said cylinder adapted to admit of a comparatively free displacement of the liquid in the dash pot during a portion of the dash pot piston movement; a restricted by-pass around the said pocket in the direction of movement of the dash pot; and means for adjusting the capacity of said by-pass, substantially as described.

11. In a tire building machine, the combination with a spinner carriage; of a cylinder adapted to receive fluid pressure; a piston connected with said carriage to produce the movement thereof; a dash pot cylinder; a piston in the said dash pot cylinder connected with the main piston; a pocket in said cylinder adapted to admit of a free displacement of the liquid in the dash pot during a portion of the dash pot piston movement; a restricted by-pass beyond the said pocket in the direction of movement of the piston; and means for adjusting the capacity of said by-pass.

12. In a tire building machine, the combination with a spinner carriage; of a cylinder adapted to receive fluid pressure; a piston connected with said carriage to produce the movement thereof; a dash pot cylinder; a piston in the said dash pot cylinder connected with the main piston; a pocket in said cylinder adapted to admit of a free displacement of the liquid in the dash pot during a portion of the dash pot piston movement; a restricted by-pass beyond the said pocket in the direction of movement of the piston; means for adjusting the capacity of said by-pass; and a spring adapted to cause the movement of the carriage in the opposite direction.

13. In a tire building machine, the combination with a spinner carriage; of a cylinder adapted to receive fluid pressure; a piston connected with said carriage to produce the movement thereof; a dash pot cylinder; a piston in the said dash pot cylinder connected with the main piston; a pocket in said cylinder adapted to admit of a free displacement of the liquid in the dash pot during a portion of the dash pot piston movement; a restricted by-pass beyond the said pocket in the direction of movement of the piston; means for adjusting the capacity of said by-pass; a spring adapted to cause the movement of the carriage in the opposite direction; and a check valve in the dash pot piston to permit the same to pass freely through

the liquid in the dash-pot while the spring is acting.

14. In a tire building machine, the combination with a spinner; of a rotatable shaping core; automatic means for moving said spinner toward the axis of said core; and liquid means for regulating the movement of said spinner toward said core.

15. In a tire building machine, the combination with a rotatable shaping core; of a spinner; a fluid pressure operated device for moving said spinner toward said core; and liquid means for regulating the movement of said spinner.

16. In a tire building machine, the combination with a spinner carriage; of one or more spinners mounted thereon; a fluid pressure motor adapted to operate the said carriage; and a dash pot to control the movement of said carriage when acted upon by said motor.

17. In a tire building machine, the combination with a rotatable core adapted to receive a strip of fabric; of a spinner; pressure-fluid operated means for automatically moving said spinner toward the axis of rotation of the core and for then maintaining said spinner constantly in yielding engagement with such fabric; means for yieldingly holding said spinner away from the core; and a manually operated device for pressing said spinner into contact with the fabric on the core.

18. A tire-making machine including a support, a carriage thereon, a tire-form juxtaposed to the support, power-operated means comprising fluid-pressure operated mechanism for advancing the carriage toward the form, power-operated means for returning it to normal position, and a pressing-member on the carriage normally out of contact with the form and positionable into contacting relation with the form by said pressure-operated mechanism and whereby it is maintained in yielding engagement with fabric on the form.

19. A tire-making machine including a support, a carriage thereon, a tire-form juxtaposed to the support, fluid-pressure operated means for advancing the carriage toward the form, means for arresting such advancing movement of the carriage, a spring motor for returning it to normal position, and a pressing member on the carriage normally out of contact with the form and positionable into contacting relation with the form by said pressure-operated mechanism and whereby it is maintained in yielding engagement with fabric on the form.

20. A tire-making machine including a tire-core, a carriage movable in relation thereto, fabric-pressing devices on the carriage, means for moving said devices in relation to each other, and pressure-fluid operating means for advancing the carriage to-

- ward the core and for maintaining said pressing devices in yielding engagement therewith.
21. A tire-making machine including a tire-core, a carriage movable in relation thereto, fabric-pressing devices on the carriage, and pressure-fluid operating means for advancing the carriage toward the core to engage said pressing devices therewith and for simultaneously maintaining said devices in yielding engagement with the core.
22. A tire-making machine including a tire-core, a carriage movable in relation thereto, fabric-pressing devices on the carriage and normally out of contact with the core, and pressure-fluid operating means for advancing the carriage toward the core to effect engagement therewith of said pressing devices and, then, for simultaneously maintaining said devices in yielding engagement with fabric on the core.
23. A tire-making machine including a tire-core, a carriage movable in relation thereto, fabric-pressing devices on the carriage and normally out of contact with the core, pressure-fluid operated means for advancing the carriage toward the core to effect active engagement therewith of the pressing devices, said means also operating, then, to maintain said devices in yielding engagement with fabric on the core, and manually-operated means active on said devices and operable independently of the movement of the carriage and during the advancing movement of the carriage for actuating the devices relatively.
24. A tire-making machine including a tire-core, a carriage movable in relation thereto, fabric-pressing devices on the carriage, and means for effecting advancing movement of the carriage toward the core including instrumentalities for effecting different speeds of the carriage at different stages of its travel toward the core.
25. A tire-making machine including a tire-core, a carriage movable in relation thereto, fabric-pressing devices on the carriage, means for effecting advancing movement of the carriage toward the core including instrumentalities for effecting different speeds of the carriage at different stages of its travel toward the core, and independent means for returning the carriage to starting position.
26. A tire-making machine including a tire-core, a carriage movable in relation thereto, fabric-pressing devices on the carriage, pressure-fluid operated means for effecting advancing movement of the carriage toward the core, and means for effecting different speeds of the carriage at different stages of its travel toward the core.
27. A tire-making machine including a tire-core, a carriage movable in relation thereto, fabric-pressing devices on the carriage, pressure-fluid operated means for effecting advancing movement of the carriage toward the core, means for effecting different speeds of the carriage at different stages of its travel toward the core, and independent means for returning the carriage to starting position.
28. A tire-making machine including a tire-core, a carriage movable in relation thereto, fabric-pressing devices on the carriage, pressure-fluid operated means for effecting advancing movement of the carriage toward the core, means for effecting different speeds of the carriage at different stages of its travel toward the core, and means for varying the operation of said speed-controlling instrumentalities.
29. A tire-making machine including a tire-core, a carriage movable in relation thereto, pressure-fluid operated means for effecting an advancing movement only of the carriage toward the core, means for automatically arresting the carriage at a point in predetermined relation to the core, and power-operated means for effecting a receding movement of the carriage.
30. A tire-making machine including a tire-core, a carriage movable in relation thereto, pressure-fluid operated means for effecting an advancing movement only of the carriage toward the core, means for varying the speed of the carriage during such advancing movement, means for automatically arresting the carriage at a point in predetermined relation to the core, and power-operated means for effecting a receding movement of the carriage.
31. A tire-making machine including a tire-core, a carriage movable in relation thereto, pressure-fluid operated means for effecting an advancing movement only of the carriage toward the core, means for varying the speed of the carriage during such advancing movement, means for automatically arresting the carriage at a point in predetermined relation to the core, and a quick-returning means active on the carriage to effect a receding movement thereof.

In testimony whereof, I have signed my name to this specification in the presence of two subscribing witnesses.

FREDERIC C. MORTON.
